Inventor:

Sverre Lillelien

By *June Danielske*
Attorney.

UNITED STATES PATENT OFFICE.

SVERRE LILLELIEN, OF RJUKAN, NORWAY.

COLLAPSIBLE MUSIC RACK.

Application filed June 18, 1925, Serial No. 38,050, and in Norway June 24, 1924.

The present invention has for its object a collapsible music-rack, adapted to stand on the floor or a table or to be fastened on a wall. The music-rack according to the present invention comprises an upper member, shaped as a broad inverted U, to the downwardly extending side members of which there are hinged extension rods, carrying a slidable rest plate for the music sheet, the lower free ends of said extension rods being connected by means of links with backwardly extending arms, the free ends of which are connected by means of a cross rod with vertical rods, the upper ends of which are pivotally connected with a rod, adapted to be fastened with its ends in any suitable position on the extension rods hinged to the downwardly extending members of the upper inverted U-shaped member.

On the drawing a preferred form of the invention is illustrated:

Fig. 1 is a side view, and

Fig. 2 is a front view.

The upper inverted U-shaped member has its parallel side members 2 and 3 pivotally connected by means of trunnions 4 and 5 with rods 7 and 8, which carry a connecting rod 18, adapted to be fastened by means of clamping screws 19 and 20 in any convenient position on said rods 7 and 8. Near their lower ends rods 7 and 8 carry a supporting ledge 9 for the music sheet. At their ends rods 7 and 8 are connected by means of hinges with backwardly extending rods 10 and 11, the free ends of which are connected by means of pin 12 and slot 22 to upwardly extending rods 14, the free ends of which are pivotally connected by means of pins 16 to the above mentioned cross rod 18. Said rod 18 serves to support the middle part of the music sheet.

In order to fold up the rack rod 18 and

supporting ledge 9 are slid upwards against rod 1, rods 10 and 14 are folded against rods 7 and 8 and the latter are swung inwards as indicated in dotted lines on Fig. 2.

The upper horizontal rod 1 may be provided at its centre with an eye-bolt 24 for hanging the rack on the wall. Otherwise the rack may stand on a table or be mounted on a suitable support on the floor.

I claim as my invention:

1. A collapsible music-rack comprising an inverted U-shaped member; a rod pivoted to each end of said member; a supporting ledge slidably mounted on said rods; a backwardly extending rod hinged to the end of each rod; a cross rod slidably and adjustably mounted on said first-named rods; and a second backwardly extending rod secured at one end to said cross rod and the other end to the first-named backwardly extending rod, said supporting ledge and cross rod being adapted to slide into the U-shaped member and the rods being adapted to fold inwardly into the member in order to fold the music-rack together.

2. A collapsible music-rack comprising a U-shaped member having pivoted side rods; a cross rod slidably mounted on said rods and adapted to support the music; a backwardly-extending rod secured to each side rod; and a second backwardly-extending rod secured to the cross rod at each end, said last two named rods being adapted to support the U-shaped member in an upright position and said cross rod being adapted to slide against the bottom portion of the U-shaped member, and the side rods and backwardly-extending rods being adapted to fold inwardly in order to fold the rack together.

In testimony that I claim the foregoing as my invention, I have signed my name.

SVERRE LILLELIEN.
